UNITED STATES PATENT OFFICE.

JAMES A. BRADEN, OF CLEVELAND, OHIO, ASSIGNOR TO THE STANDARD PARTS COMPANY, OF CLEVELAND, OHIO, A CORPORATION OF OHIO.

DESIGN FOR A BADGE, EMBLEM, OR SIMILAR ARTICLE.

● 55,551.

Specification for Design.

Patented June 29, 1920.

Application filed January 19, 1920. Serial No. 352,619. Term of patent 3½ years.

To all whom it may concern:

Be it known that I, JAMES A. BRADEN, a citizen of the United States, and a resident of Cleveland, county of Cuyahoga, State of Ohio, have invented a new, original, and ornamental Design for Badges, Emblems, or Similar Articles, of which the following is a specification, reference being had to the accompanying drawings forming part hereof, wherein is shown a view in elevation of a badge embodying my invention.

What I claim is:—

The ornamental design for a badge, emblem, or similar article as shown.

In testimony whereof I affix my signature.

JAMES A. BRADEN.
